UNITED STATES PATENT OFFICE.

WASHINGTON KYLE SHEFFIELD AND ALBERT J. HORTON, OF NEW LONDON, CONNECTICUT, ASSIGNEES TO MECHANICAL ENGINEERING CORPORATION, OF NEW LONDON, CONNECTICUT, A CORPORATION OF CONNECTICUT.

HAND-OPERATED BULLETIN-PRINTING MACHINE.

Application filed October 6, 1923. Serial No. 666,957.

This invention relates to hand operated bulletin printing machines or devices for printing advertising and other matter, though it is noted that the invention is not limited to bulletin machines nor in some respects even to printing machines.

One object of the invention is to provide in an apparatus or device of this kind an improved type wheel and carriage control and type spacing mechanism.

Another object of the invention is to provide an apparatus or device of this kind having improved type alining mechanism.

Other objects of the invention are to improve generally the simplicity, speed and efficiency of such devices and to provide a device or apparatus of this kind which is durable, economical to manufacture and operate, and which will not get out of order.

The inventive features for the accomplishment of these and other objects are herein shown in connection with an improved bulletin printing machine which, briefly stated, comprises a main frame carrying a supply roll, a platen bar, and supporting rollers carrying a take-up roll loosely supported on the supporting rollers. Other rollers guide the paper from the supply roll to and from the platen and thence to the take-up roll. A carriage pivotal and slideable on a rail carried on the frame in turn carries a type wheel, and an index wheel operatively connected to the type wheel. A handle extending from the carriage serves to rock the carriage and press the type to the paper, and at the same time actuate a pair of escapement teeth mounted on the carriage into cooperation with a series of rollers mounted on a spacing bar to advance the carriage. A ratchet on one of the supporting rollers is engaged by a feed pawl on a line spacing lever for feeding the paper; while a detent pawl prevents retrograde motion of the ratchet, and a stop pawl prevents over feed.

Other objects of the invention will appear as the description proceeds; and while herein details of the invention are described, the invention is not limited to these, since many and various changes may be made without departing from the scope of the invention as claimed.

In the accompanying drawing, showing by way of example, one of many possible embodiments of the invention,

55

Fig. 1 is a front elevation of the machine;

Fig. 2 is an end elevation;

Figs. 3 and 4 are side elevations showing different positions of the carriage;

60

Fig. 5 is an inclined fragmental plan showing the index wheel looking in the direction of the arrow of line 5 of Fig. 3;

65

Fig. 6 is an inclined sectional view, partly in plan of the escapement bar and rollers taken on the line 6—6 of Fig. 4, looking in the direction of the arrow of said line;

70

Fig. 7 is a side elevation partly in section showing a spacing roller; and

Figs. 8 and 9 are fragmental side elevations showing the ratchet and pawls.

75

The operative parts of my improved machine are carried on a main frame comprising a pair of end members 10 formed with widely separated feet 11 and a cross piece 12 slightly above the middle part, and provided with open bearing recesses 13 receiving a shaft 14 carrying a supply roll of paper 15, pressed upon by a resistance roller 16 journaled in the ends of links 17 pivoted to the frame, to prevent overthrow of the roll. The paper passes over and under intermediate and lower paper guide rollers 20 and 21 (Figs. 2 and 3) by which paper is guided to and from the platen bar 22.

80

Uprights 23 on the top of the end members carry a top roller 25 receiving paper from the lower roller 21 to form a display field 26 (Fig. 1). A pair of parallel supporting rollers 27 and 28 (Fig. 2) are mounted at the upper part of the frame to the rear of said field. The paper passes from the top roller under these rollers 27 and 28 to the take-up roll 29 which is merely loosely supported on the supporting rollers.

85

A sleeve 30 (Fig. 3) pivotal and slideable on rail 31 mounted between said members 10 above and to the rear of the platen carries a carriage frame 34 fast on said sleeve and comprising spaced frame members 35 and 36 (Fig. 5) in which is mounted a horizontal shaft 37 carrying a type wheel 38 provided with peripheral type 39, and a bevel pinion 40 and a tooth alining wheel

90

95

100

41. A spindle 45 in radial bearings of said member 35 carries a bevel gear 46 engaging said pinion, and also carries an index wheel 47 on the spindle provided with indicating letters and characters 48^a corresponding to the type 39. A pointer 48 is carried on the said carriage frame and disposed over said indicating wheel, for selecting the type to be printed.
- 10 49. A handle 50 extending from the carriage frame serves for rocking the type to the platen as in Fig. 4. A forward extension 51 of said carriage frame comprises an upper member 52 and a lower member 53, to which latter is pivoted an inking roller casing 55 carrying therein an inking roller 56 pressing against the type. A restoring elbow lever 58 pivoted at its elbow part to the carriage frame has a long arm 59, Fig. 3; provided with an end roller 60 bearing against a spacing bar 61. A spring 63 tensioned between said casing 55 and the short arm of the restoring lever holds the ink roller 56 pressed against the type and said end roller 60 pressed against the spacing or escapement bar 61 thereby to move the type wheel from the platen after printing has been effected. An alining pawl 65 pivoted on the carriage frame is acted upon by a spring 66 tensioned between a pin 68 on the pawl and said short arm, whereby the pawl is caused to engage between the teeth of the alining wheel 41 as the type is pressed against the paper, thereby to aline the type. A detent finger 67 carried on said elbow lever engages the pin 68 when the type wheel is retracted, to lift the pawl from the teeth to permit the type wheel to turn to select another character.
- 20 68. A series of rollers 70 (Figs. 6 and 7) mounted on said spacing bar 61 cooperate with a pair of relatively offset inwardly pointed type spacing teeth 71 and 72 mounted on the lower face of said upper member 52 and snugly disposable between said rollers. Said teeth have parallel advance and rear positioning faces 73 and 74 engaging the rollers, and beveled cam faces 76 and 77 engageable with the rollers respectively to advance the carriage a half space during the forward stroke, and a half space during the back stroke of the type wheel. The forward end 77 of the tooth 71 is pointed for the easy insertion of the tooth between the rollers when the carriage is oscillated from the position of Fig. 3 to that of Fig. 4. In the position of Fig. 3, the carriage may be easily slid toward either end of the rail for wide spacing, paragraphing or display work.
- 25 78. A line spacing paper feed ratchet 78 (Fig. 8) fast on the rear supporting roller 27 has abrupt teeth 79 engaged by a feed pawl 80 on a line spacing lever 81 loosely mounted on the journal of said rear roller.

A spring 83 compressed between the tail of said pawl and a socket 84 of the lever yieldably holds the pawl in engagement with the teeth. A detent pawl 85 pivoted on the main frame prevents retrograde motion of the roller; while a stop pawl 86 engaging the advance faces of the teeth for preventing over feed, is provided with a tail 88 engageable by a lifting finger 89 on the lever to hold the stop pawl disengaged from the ratchet as the feed pawl 80 moves to its most retracted position (Fig. 8) and advances the ratchet a short distance, whereupon the finger 89 releases the stop pawl for engagement with the crown of the tooth ready to engage and stop the next tooth when the paper has been fed one line space, as in Fig. 9.

The operation of the device is very simple, and obvious from the foregoing. 85

The supply roll 15 is put in place, the paper threaded up as in Fig. 2 and started on the take-up roll 29. The carriage is then slid laterally to near the point where the first letter is to be printed and the index wheel rotated by hand, thus inking the type until the character to be printed is opposite 48. The handle 50 is then forced down by hand, thus forcing the pointed end 77 (Fig. 6) between the rollers 70. Continued downward movement of the handle carries the tooth 71 past the rollers and brings the cam face 77 into camming engagement with the roller 70, moving the carriage a half space just before the type is pressed to the paper. This movement brings the alining wheel 41 into engagement with the pawl 65, thus slightly rotating the type wheel, if necessary, and alining the type accurately. 100

The handle 50 is then released, and on the return stroke, the cam face 76 is brought into camming engagement with a spacing roller, thus spacing the carriage another half letter-space. The above operation is repeated until a word is spelled. 110

The space between the words is obtained either by sliding the carriage to the right without oscillating it, or by repeating the above described operation, except that the type is not brought into contact with the paper. 115

After the line is completed, the paper is fed a line space for the next line merely by drawing the lever 81 toward the operator to the position of Fig. 9, whereupon the supporting roller and paper are stopped by the pawl 86. The lever 81 is then allowed to fall to the position of Fig. 2 against the end member 10, whereby the pawl 85 holds the ratchet and paper against retrograde movement. 125

We claim as our invention:

1. In combination, a frame comprising end members; a platen thereon; a rail shaft mounted between said end members above 130

- and to the rear of the platen; a sleeve pivotal and slideable on said shaft; a carriage frame fast on said sleeve and comprising spaced frame members one of which 5 has upwardly radially alined bearings; a horizontal shaft mounted in the mid part of the frame; a type wheel on said shaft provided with peripheral type, and comprising a bevel pinion; a spindle in the radial 10 bearings; a bevel gear on said spindle engaging said pinion; an indicator wheel on the spindle provided with indicating letters and characters corresponding to those of the type wheel; a pointer carried on the said 15 carriage frame and disposed over said indicating wheel; a handle extending from the carriage frame for rocking the type to the platen; and spacing means to advance the carriage.
- 20 2. In combination, a platen; a rail; a carriage oscillatable and slideable on said rail and having a member extending therefrom; a type wheel on said carriage and oscillatable about the axis of said rail; a spacing bar; a series of rollers mounted on said 25 bar; and a pair of relatively offset inwardly pointed forward and rear spacing teeth mounted on the lower face of said member and snugly disposable between said rollers 30 and having paralled advance and following positioning faces engaging the rollers and having beveled cam faces engageable with the rollers to advance the type wheel a half type-space during the forward oscillation 35 and a half type-space during the reverse oscillation of the type wheel.
3. In combination, a platen; a rail; a carriage pivotal and slideable on said rail; a type wheel on the carriage; a bar; an inking 40 roller casing pivoted on said carriage; an inking roller therein; a restoring lever pivoted to the carriage and having an arm bearing against said bar; and a spring tensioned between said lever and casing, whereby the inking roller is pressed against the 45 type and said type wheel is moved from the platen.
4. In combination, a platen; a rail; a carriage pivotal and slideable on said rail; a type wheel on the carriage; means to advance the carriage; a bar; a forward extension on said carriage frame, comprising upper and lower members; an inking roller casing pivoted on said lower member; an 50 inking roller therein pressing against the type; a restoring elbow lever pivoted at the elbow part to the carriage frame and having a long arm provided with an end roller bearing against the escapement bar, and a 55 short arm; and a spring tensioned between said short arm and casing, whereby the roller is pressed against the type and said end roller is pressed against the escapement bar to move the type wheel from the 60 platen.
5. In combination, a platen; a rail; a carriage pivotal and slideable on said rail; a typewheel mounted in the carriage; a tooth alining wheel fast on the type wheel; a bar; a spring pressed restoring lever pivoted to the carriage and bearing against said bar; an alining pawl on the carriage and spring pressed to engage between said teeth; means to lift the pawl from the teeth when the type wheel is retracted; and spacing means for 70 the carriage.
6. In combination, a platen; a rail; a carriage pivotal and slideable on said rail; a type wheel mounted in the carriage; a tooth alining wheel fast on the type wheel; a 80 spring pressed restoring lever pivoted to the carriage and comprising a short arm and a long arm, the latter bearing against the bar; an alining pawl pivoted on the carriage frame; a spring tensioned between the pawl 85 and said short arm whereby the pawl is caused to engage between the teeth of the alining wheel as the type is pressed to the platen, thereby to aline the type; a detent finger carried on said restoring lever and 90 engaging a pin on said pawl when the type is retracted to lift the pawl from the teeth to permit the type wheel to turn; and spacing means to advance the carriage.
7. In combination, a main frame comprising a pair of end members formed with widely separated feet and slightly above the middle part with open bearing recesses; a supply roll mounted in said recesses; a platen bar fixed between said members, intermediate and lower paper guide rollers over and under which paper is guided to and from the platen; uprights on the top of the end members, a top roller supported 95 on the uprights and receiving paper from the lower roller to form a display field; a rail on the frame; a carriage pivotal and slideable on said rail; and a type wheel on the carriage and engageable with the paper on the platen.
8. In combination, a rail; a type carriage pivotal and slideable on said rail; a bar; projections on said bar; and spacing teeth fixed on the carriage cooperating with said projections to advance the carriage; said 105 carriage being normally disposed with the teeth out of contact with said projections to permit unrestricted sliding of the carriage on the rail.
9. In combination, a rail; a type carriage oscillatable and slideable on said rail; a bar; a series of rollers spaced on said bar; and spacing teeth on the carriage engaging with said rollers to advance the carriage when the carriage is oscillated.
10. In combination, a platen; a rail; a carriage pivotal and slideable on said rail; type carried by the carriage; a bar; and a spring pressed restoring lever pivoted to the carriage and provided with a roller bear- 110 115 120 125 130

- ing against said bar whereby the type is retracted from the platen.
11. In combination, a platen; a rail; a carriage pivotal and slidable on said rail; a type wheel mounted on the carriage; a bar parallel to said rail; a restoring lever pivoted to the carriage and bearing against the bar; a carrier on the carriage; inking means thereon to engage the type; and a spring tensioned between said lever and carrier to press the lever on the bar and the inking means against the type.
12. In combination, a rail; a carriage pivotal and slidable on said rail; a type wheel mounted on the carriage; a toothed alining wheel fast on the type wheel; a bar parallel to said rail; a restoring lever pivoted to the carriage and bearing against the bar; an alining pawl on the carriage adapted to engage between the teeth of the alining wheel; a gage between the teeth of the alining wheel; a spring tensioned between said lever and pawl to press the lever on the bar and the pawl against the side teeth; and means to lift the pawl from the teeth when the type wheel is retracted.
13. In combination, a platen; a rail; a carriage pivotal and slidable on said rail; a type wheel mounted in the carriage; a toothed alining wheel fast on the type wheel; a bar parallel to said rail; a spring pressed restoring lever pivoted to the carriage and bearing against the bar; an alining pawl on the carriage adapted to engage between the teeth of the alining wheel; and a finger carried on the restoring lever to lift the pawl from said teeth when the type wheel is retracted.
14. In combination, a platen; a rail; a carriage pivotally and slidably suspended from the rail below the rail; type on the carriage; and a handle on the carriage adapted on downward movement to press the type to the platen.

W. KYLE SHEFFIELD.
ALBERT J. HORTON.
